DESIGN FOR A FLOOR HEATER UNIT

Fred M. Young, Racine, Wis.

Application May 2, 1940, Serial No. 92,037

Term of patent 14 years

To all whom it may concern:

Be it known that I, Fred M. Young, a citizen of the United States, residing at Racine, in the county of Racine and State of Wisconsin, have invented a new, original, and ornamental Design for Floor Heater Units, of which the following is a specification, reference being had to the accompanying drawing, forming a part thereof.

Fig. 1 is a front elevational view of a floor heater unit showing my new design;

Fig. 2 is a fragmentary top plan view thereof with a portion of the corner on the line 2-2 of

Fig. 1 broken away for convenience of illustration; and

Fig. 3 is an end elevational view thereof.

The end not shown is similar to the end shown. The characteristic features of my design reside in a floor heater unit having fluted front and end panels as shown.

I claim:

The ornamental design for a floor heater unit, as shown and described.

FRED M. YOUNG.
